(57) **CLAIM**

The ornamental design for a device mount, as shown and
described.

DESCRIPTION

FIG. 1 is a front perspective view of a device mount
according to the present invention;

FIG. 2 is a rear perspective view of the device mount;

FIG. 3 is a top view of the device mount;

FIG. 4 is a front view of the device mount;

FIG. 5 is a bottom view of the device mount;

FIG. 6 is a rear view of the device mount;

FIG. 7 is a left side view of the device mount; and,

FIG. 8 is a right side view of the device mount.

The structural features depicted by broken lines have been
shown for the purpose of illustrating portions of the device
mount that form no part of the claimed design.
